UNITED STATES PATENT OFFICE.

ELISHA F. PARKS, JR., OF TIMONIUM, AND PHILIP G. LANG, JR., OF BALTIMORE,
MARYLAND.

TRIMMER-BELT ATTACHMENT.

Application filed September 10, 1920. Serial No. 409,507.

To all whom it may concern:

Be it known that we, ELISHA F. PARKS, Jr., and PHILIP G. LANG, Jr., citizens of the United States, residing, respectively, at Timonium, Baltimore County, in the State of Maryland, and Baltimore city, in the State of Maryland, have invented certain new and useful Improvements in Trimmer-Belt Attachments; and we do hereby declare the following to be a full, clear, and exact description of the invention, such as will enable others skilled in the art to which it appertains to make and use the same.

Our invention relates to attachments for trimmer belts, such as are used in storing cargoes of coal or other materials on board ships, or in placing said materials in bins or other storage receptacles.

Among the objects of our invention are:

20 To produce an attachment which can be readily secured to any approved form of belt.

To produce an attachment which can be blanked and shaped readily by means of dies 25 so that the same can be furnished at a reasonable cost.

Heretofore, attachments have been secured to trimmer belts in a variety of ways, but the mode of attachment was usually complicated or required a packing of leather under the attachment.

By the use of our improved attachment, the use of complicated securing devices and leather packing is entirely avoided.

35 In carrying out our invention we make use of the instrumentalities illustrated in the accompanying drawings, in which:

Figure 1 is a perspective view of a portion of trimmer belt showing two forms of our 40 improved attachment secured thereupon.

Fig. 2 is a side elevation of said belt and attachment.

Fig. 3 is a view of either form of our improved trimmer attachment viewed in the 45 direction of the arrow 3 in Fig. 2 but with the teeth 10 not bent over.

In the drawings:

5 is a belt which may be of leather or any 50 approved woven fabric, of any suitable width, driven in any approved manner and controlled by any suitable mechanism so that the faces of the attachments will be directed against the bulk material that is to be trimmed.

The attachments shown at 6 consist of a flat top 7 having ends 8—8 bent at right angles thereto, said ends terminating in the approximately straight edges 9—9 from which project the teeth 10. The teeth 10 may be of any approved contour.

60 In applying our improved attachments to the belt 5 the teeth 10 are driven through the body of the belt and then bent over as shown in Fig. 2 so as to secure said attachments to the belt.

65 It is to be noted that when the teeth 10 are driven through the belt 5, as just described, the edge 9 presses against the adjacent side of said belt and thus the top 7 is secured at the proper distance from the surface of 70 said belt.

75 It is evident that the ends 8 may be of any suitable length so that the top 7 will stand at any suitable distance from the surface of the belt 5.

The attachment shown at 11 is substantially the same as the attachment shown at 6 excepting that the top 12 is made sinuous so that the under surface thereof will contact with the adjacent surface of the belt 5 80 substantially midway between the ends 13—13 for the purpose of giving additional rigidity to said top.

85 It is evident that with this structure the ends 13—13 may be placed any distance apart and there may be as many contacts as are desired between said ends of the under surface of the top 12 with the abutting surfaces of the belt 5.

90 The attachment shown at 11 is otherwise the same as the attachment shown at 6 and is secured to the belt 5 in a similar manner.

95 In Figure 1 we have shown three of each type of our improved attachment secured in mutual alignment, but it is to be understood that we may use any number in alignment, or that we may use them staggered, or that we may make them of any width so that they cover practically the full width of the belt, if desired.

100 Thus, we produce a simple, cheap and efficient attachment with trimmer belts, which can be secured in place at a minimum cost.

We claim:

105 1. A trimmer belt attachment comprising a sinuous top, bent ends each having teeth thereon and straight edges between said teeth, said straight edges being in substan-

tially the same plane as the lower surface of said top.

2. The combination with a trimmer belt, of an attachment secured thereon, said attachment comprising a top, bent ends each having teeth thereon and straight edges between said teeth bearing against one side

of said belt, said teeth passing through said belt and bent against the other side thereof.

In testimony whereof, we affix our signatures.

ELISHA F. PARKS, JR.
PHILIP G. LANG, JR.
